UNITED STATES PATENT OFFICE.

JOHN FLESHER NEWSOM, OF PALO ALTO, CALIFORNIA; JOHN BRANNER NEWSOM
EXECUTOR OF SAID JOHN FLESHER NEWSOM, DECEASED.

PROCESS OF ORE DREDGING.

Application filed June 20, 1923, Serial No. 646,699, and in the Federated Malay States February 7, 1923.

Owing to the low value of the material handled by ore dredges, it is imperative to handle very large volumes, otherwise the operation cannot succeed, and therefore one of 5 the chief objects to be arrived at in ore dredging is to obtain the greatest possible capacity of ore washing treatment, having regard to the confined space upon the ore dredge within which this treatment must be 10 accomplished, and the ability to successfully wash and recover the ore from the barren material after it has been disintegrated therefore becomes one of the limiting factors in ore dredge capacities.

15 The necessary limit in both floor space and head room which (along with accessory driving apparatus) can be made available for treatment apparatus on a floating pontoon, combined with the necessity for treatment of 20 many thousands of cubic yards of material per day on a floating pontoon is one of the fundamental and inherent differences between ore dredging, and all other mining operations, which has led to its development as a 25 process separate and distinct from all other branches of mining.

It follows therefore that one of the most important functions of the ore dredge should be to discard all of the worthless material 30 possible, without undue loss of ore, before passing the resulting material on to the final ore saving devices on the dredge, so that any given unit of material handled by those devices will represent the greatest possible number of units of material as it originally stood 35 in the bank.

In the ore dredging process as hitherto conducted, the practice has been to discard only the coarse barren materials direct to the waste 40 heap, thus materially reducing the volume of material to be treated on the ore saving device, only when there is a large percentage of such coarse worthless classes in the original bank, but the antithetic step to accomplish 45 the same object of reduction of bulk, viz: that of discarding direct to the waste heap all of the finest sizes of barren sands, clays etc. possible, and by this fine discarding step to greatly reduce the volume, and at the same 50 time to improve the character of the material that must be handled by the ore saving devices, has not been practiced in the ore dredging process hitherto.

The essential steps in the treatment of the 55 bank materials in the ore dredging process

as hitherto conducted, are indicated in the drawings accompanying this specification in Figures 5 (an elevation view) and 6 (a plan view) in skeleton of an ore dredge, and are designated by the Roman numerals as given 60 below. These essential steps are as follows:—

I. The excavation of the material from the bank by bucket, suction cutter, gravel pump, or other type of excavators.

II. The disintegration of the material and 65 the sorting out and rejecting, usually by means of screens or grizzlies, of the coarse gravel, boulders, rocks, and other coarse grades of worthless materials, through tailings elevators or stone shoots.

III. Treatment of the whole of the materials remaining after this preliminary sorting and coarse rejection step, upon sluices with riffles as indicated, or upon other concentration devices.

The percentage of waste material that can be eliminated by the screening step depends entirely upon the coarseness of the material in the bank. Where there is a large percentage of coarse gravel, rocks, and boulders, as 80 occurs in many placer deposits, then a large percentage of the original bank materials is eliminated by the screening process, and the resulting quantity of material to be treated on the sluices, or other devices, is correspondingly small, and large daily capacities of the material as it originally stood in the bank can be successfully washed. Where however, the proportion of coarse material in the bank is very small, and the percentage of the finest 90 gravels, sands, and clays is correspondingly large, then the eliminating capabilities of the screening step without ore loss becomes almost nil, and practically the total quantity of the bank material that is brought on board 95 the dredge must then be treated in the sluices or other concentrating devices. This results either in the overcrowding of those devices, and high ore losses, or in reducing the yardages handled in order to prevent such overcrowding and loss, and makes it impractical to handle the materials and make a close saving with such machines as jigs.

These smaller sizes of material are invariably the most difficult to treat in large quantities in sluices or other ore concentrating devices, and at the same time to make a close saving of the ore contained. It is to overcome this inherent weakness in the present ore dredging process, by the direct elimination 105 110

of the finest sized materials before final treatment on the ore saving devices that the following improvement in the dredging process has been devised.

5 The steps in the improved process are as follows, again referring to Figures 5 and 6 of the drawings and the Roman numerals as below:—

10 I. The excavation of the material by the ordinary bucket, suction cutter, gravel pump, or other type of dredge, as hitherto has been done.

15 II. The disintegration of the materials thus excavated, and the screening out and rejection of the coarse rocks, boulders, gravel or other coarse barren materials, as has hitherto been done.

20 III. The treatment of the ore bearing materials, which result from the preliminary screening operation (step II above) and pass through the screen apertures, in a desanding, or classifying device, the essential object of which is to sort out and discard to the waste heap the worthless finer sands and slimes and 25 to concentrate the valuable ore into the intermediate sizes of materials, which intermediate sized material, only, is fed to the subsequent ore treatment devices, step III.

30 IV. Treatment of the ore-bearing materials resulting from step II^a on sluices or other devices as has hitherto been done.

It will thus be seen that while the ordinary ore dredging process consists, after excavation, in the direct elimination of the coarser 35 barren materials only, followed by the treatment of all of the intermediate and finer grades of barren materials mixed up together, my improvement consists in the elimination of the coarsest, boulders, gravel and other 40 barren materials by means of screens as heretofore, but follows this step by the further elimination of the finer classes of material designated as step II^a, so that only the intermediate sizes of the material (as it stood in 45 the bank) contain the ore, and this portion of the material only is treated by the final ore treatment devices; that is to say, that while the ore dredging process as hitherto practiced discards directly, before final treatment, only 50 the coarsest sized classes of worthless material, my improved process consists in the direct discard of both the coarsest and the finest sized classes, before conveying the medium sized classes of bank material (i. e. the 55 coarsest sands only) containing the bulk of the ore to the final ore treatment devices.

This elimination of the finer classes of worthless material accomplishes two very beneficial things which have hitherto not been 60 accomplished in the ore dredging process viz: (A) It greatly reduces the bulk of the material to be handled on the ore washing devices by the removal of precisely those classes of barren material which are the greatest obstacle to rapid washing with a

close saving of ore, and (B) it leaves the ore values in a greatly reduced bulk of material composed of the coarser classes of sands only; that is to say, material of the sort that can be most easily and rapidly washed on 70 any large capacity efficient ore saving devices such as sluices, which are commonly in use on ore dredges, with a closer saving of ore than heretofore; and of such a character that it can also be handled in lower capacity ore 75 saving devices which result in a closer saving than sluices as, for example, jigs, without clogging such devices with an unnecessary volume of worthless fine material.

In the elimination of the coarser sized materials, the screening devices in general use can be used. While in the succeeding step, the subject matter of my invention, that of eliminating the finer sizes of barren material, the well known rapid current, shallow box 80 type of desanding device, known as "spitzkasten", or sand wheels, or any other type of device which eliminates the worthless finer sands and slimes from the ore bearing material before it is washed, may be used, but 90 I prefer the use of a deep box, double current classifier because the capacity of this device, with equal classifying and settling qualities is greater than that of other forms of desanding, classifying and dewatering devices. 95

The drawings accompanying this specification make clear the nature of my improvement in which:—

Fig. 1 is a plan view of the stern portion of a bucket type of ore dredge showing a deep 100 box double current classifier as the desanding apparatus, followed by jigs on the port side, and followed by ordinary sluices on the starboard side.

Fig. 2 is a cross-section on line B B of Fig. 1, showing the relations of the desanding apparatus to the treatment devices.

Fig. 3 is a longitudinal section of Fig. 1 on the line (AA) showing the desanding apparatus in combination with the jigs.

Fig. 4 is a longitudinal section on line C—C of Fig. 1 showing the combination of the desanding device followed by ordinary ore sluices on the starboard side and jigs on the port side.

Fig. 5 is a general sectional view of an ore dredge showing the sequence of fundamental treatment steps in the ore dredging process as heretofore practiced, and also with my improved process.

Fig. 6 is a plan view of the dredge shown in Figure 5. In Figures 5 and 6 the fundamental steps only in the old and the improved process are indicated, and Roman numerals are used.

The following description makes clear the process by which the improvement is brought about. In this description and in the above figures the ordinary bucket type of dredge is used for purposes of illustration, but, it 130

will be understood that the combination forming the improved method of treatment may be likewise used on suction cutter dredges on gravel pumps, or in other types 5 of placer or alluvial ore dredging operations.

Referring now in detail to the drawings, Figures 1 to 4 inclusive, in which the same reference numerals are used for the same parts, and in which the ordinary floating 10 bucket type of ore dredge is used for purposes of illustration. The ore bearing material is elevated by buckets (1) from which it dumps into the feed shoot (2), and thence into the revolving screen, (3), in this revolving 15 screen which is provided with perforations, the coarse rocks and gravel and other coarse extraneous materials are screened out and dumped from the lower end of the screen into the stone shoot, or other discarding apparatus, (4) from whence the coarser materials 20 are discarded into the pond or the waste heap at (5). In the ordinary dredging process the finer grades of materials which pass through the perforations in the screen issue 25 from gates (6) under the screen, and thence all this fine material which has passed through the perforations in the screen passes directly on to the sluices (7) or other ore treatment devices, whence the waste material 30 is discharged at 13 or at 14.

The above is the description of the essential and vital steps in the process of ore dredging as hitherto practiced. From these steps it is obvious that only the coarser barren materials 35 are discarded in the treatment process prior to the actual ore concentration operation, and that all materials which pass through the perforations in the screen, pass on for further treatment in the real ore concentration machines. These materials are essentially un- 40 classified other than by the very rough classification which is accomplished in the screening operation. Furthermore, the smallest sized holes practical to use in screens in dredging operations without clogging by 45 small gravel and coarse sand grains are approximately $\frac{1}{4}$ to $\frac{3}{8}$ of an inch in diameter.

It is therefore obvious that in this process only that portion of the bank material which 50 is coarser than the diameters of the holes in the screen can be discarded direct into the tailings piles without being sent on to further treatment devices by means of which the final concentration is accomplished, and whose 55 treatment capacities with close saving of ore are always limited. Accordingly where the great bulk of bank material is composed of fine sands whose grains are smaller than the holes in the screen (3), the percent of material discarded by the screen becomes 60 practically nothing. In other words the screen (3) in the ordinary dredging process is the only machine for the elimination of waste material prior to final ore treatment on the dredge, and in cases where there is no coarse 65

material, its function in this respect ceases, thus causing overcrowding of the succeeding treatment machines with the finer sized classes of material which are the most difficult to treat, and resulting in increased loss of 70 the valuable mineral.

It is to overcome, as far as possible, this vital difficulty in the ordinary dredging process that my improvement has been introduced. In my improved process, after the bank material has passed into the screen and all possible coarse material has been removed by the screen as in the ordinary process, the resulting fine materials which have passed through the apertures in the screen issue from the 80 gates (6) under the screen and then by means of a feed launder pass directly into a desanding device (9) which may consist of the rapid current shallow box "spitzkasten" type or of sand elevators of any other type of de- 85 sanding device, but preferably is of a deep box double current type, as indicated in the drawings. In this classifying or desanding step, and in the device shown, the finer sands and slimes are carried away from the desanding device (9) through the overflow (10) into the slime launders (11) from which they are discharged at (12). The coarser and 90 heavier grains of sand and ore settle into the hoppers, a few of which are designated by the 95 numeral (16) in the desanding device (9) according to their specific gravities, and pass out through the openings, a few of which are designated by the numeral (17) at the bottom, of the hoppers. These sizes of materials 100 which carry sufficient percentage of ore are conveyed by the launders (18) to further treatment devices such as sluices (7), or jigs (8).

It will be understood that in a classifier of 105 the deep box double current type fresh water is introduced so as to produce a second and lower current of fresh water under the current of pulp bearing water. This fresh water is available for use in the ore separation devices such as sluices or jigs, and is much more efficient than the thick, slimy water, such as 110 in the upper current of the classifier.

It is obvious from the above description 115 therefore that in my improved process all coarse materials which the limitations of screening permit, will be discarded directly into the waste heap by means of the screen (3) as heretofore, and that following this discarding step, all of the finer worthless materials which may be separated from the valuable minerals by means of the rates of settling in water prior to final treatment, are likewise discarded directly to the waste heap, without 120 going to further concentration devices; and these devices are thus relieved from treating this fine material, which is the most difficult sort of material for them to treat in large capacities. It is also obvious that the bulk 125 of the material to be treated in the ore saving 130

machines will be much reduced as compared with the bulk that must be treated in the present ore dredging process, that is to say that any given unit of material handled by the ore saving machines will represent a much greater quantity of the bank material than has hitherto been possible, and the real capacity of the ore saving devices, as related to the bank material being worked, will therefore be greater than heretofore, and also a closer saving of ore can be made.

It is also obvious (if classifiers are used), that there will be a definite classification of the sands and ore caught, into various sizes, which may be taken on for further treatment to the devices adapted to best handle the different sizes; these devices may then work to their maximum capacity both in ore saving and in material treated.

20 By means of my improvement in the method of handling the material therefore the bulk of the material carrying the ore, which must be treated in the ore saving machines, will be so improved in character and reduced 25 in volume that it can be treated with closer ore saving and greater efficiency on such large capacity devices as the present type of sluices than has hitherto been possible, and so that other well known lower capacity but close ore 30 saving machines as for example jigs, which have hitherto been unsuccessful on dredges working fine sandy and clayey alluvial deposits, can successfully treat the material, all of which will result in larger working 35 capacities and closer saving of ore than have been hitherto possible, and the chief objects of the improved method of treatment will be thus attained.

Having now particularly described and 40 ascertained the nature of my said invention and in what manner the same is to be performed, I declare that what I claim is:—

1. The process of ore dredging comprising excavating the material, separating and 45 rejecting the coarsest and the finest classes of the excavated material and treating the remaining intermediate classes of the material to recover the valuable metal therefrom after the coarsest and finest classes have been 50 removed.

2. The process of ore dredging comprising excavating the material, separating and discarding the coarse classes, separating and discarding the fine classes and classifying the intermediate classes into separate and different intermediate classes.

3. The process of ore dredging comprising excavating the material, separating out and rejecting the coarse classes, separating out 60 and rejecting the fine classes by carrying them off in a current of water, and treating the intermediate classes with fresh water after the coarse classes and fine classes have been removed.

65 4. The process of ore dredging comprising

excavating the material, separating out and rejecting the coarse classes, separating out and rejecting the fine classes by carrying them off in a current of water, and treating the intermediate classes in ore separation devices after the coarse classes and fine classes have been removed.

5. The process of ore dredging comprising excavating the material, separating out and rejecting the coarse classes, separating out 70 and rejecting the fine classes by allowing the current of water in which they are suspended to carry them off, causing a current of fresh water to flow under said first current, the intermediate classes leaving said first current 75 passing through said second current, and treating the intermediate classes with said fresh water after the coarse classes and fine classes have been removed.

6. The process of ore dredging comprising excavating material, separating out and rejecting the coarse classes, separating out and rejecting the fine classes by allowing the current of water in which they are suspended to carry them off, causing a current of fresh water to flow under said first current, allowing the intermediate classes leaving said first current to pass through said second current, classifying said intermediate classes into separate and different intermediate classes according to 90 their rates of settling in said currents, and treating the intermediate classes with said fresh water after the coarse classes and fine classes have been removed.

7. An apparatus for recovering metal from submerged metal bearing deposits comprising a float adapted to be held adjacent said deposits, means on the float for excavating the material of the deposit, means on the float for screening out the coarse classes from the excavated material, a deep box double current classifier on the float for carrying off the fine classes in a current of water and allowing the different intermediate classes to settle into different hoppers, and metal saving devices on the float for recovering the metal from said intermediate classes after the coarse and fine classes have been removed.

8. An apparatus for recovering metal from submerged metal bearing deposits comprising a float adapted to be held adjacent said deposits, means on the float for excavating the material of the deposit, means on the float for rejecting the coarse classes from the excavated material, means on the float for rejecting the fine classes by carrying them off in a current of water, and metal saving devices on the float for recovering the metal from the remaining intermediate classes after the coarse and fine classes have been removed.

9. An apparatus for recovering metal from submerged metal bearing deposits comprising a float adapted to be held adjacent said deposits, means on the float for excavating the material of the deposit, means on the float for

rejecting the coarse classes from the excavated material, means on the float for rejecting the fine classes, and metal saving devices on the float for recovering the metal from the remaining intermediate classes after the coarse and fine classes have been removed.

10. An apparatus for recovering metal from submerged metal bearing deposits comprising a float adapted to be held adjacent said deposits, means on the float for excavating the material of the deposit, means on the float for rejecting worthless classes including the fine classes from the excavated material, and metal saving devices on the float for recovering the metal from the remaining intermediate classes after the worthless classes have been removed.

11. An apparatus for recovering metal from submerged metal bearing deposits comprising a float adapted to be held adjacent the submerged deposit, means on the float for excavating the material of the deposit, a classifier on the float having a series of hoppers, means for causing the material of the deposit and water to flow through said classifier to allow the different intermediate classes to settle into the several hoppers and to allow the fine classes to be carried away by the water, a plurality of jigs on the float for treating the intermediate classes delivered by said hoppers to recover the values therefrom.

12. An apparatus for recovering metal from submerged metal bearing deposits comprising a float adapted to be held adjacent the submerged deposit, means on the float for exca-

vating the material of the deposit, means on the float for separating out and rejecting the worthless classes including the fine classes, and jigs on the float for treating the remaining intermediate classes to recover the values therefrom after the worthless classes have been removed.

13. An apparatus for recovering metal from submerged metal bearing deposits comprising a float adapted to be held adjacent the submerged deposit, means on the float for excavating the material of the deposit, means on the float for separating out the worthless classes including the superfine slimes, fine sands and excess water from the material of the deposit, and jigs on the float to treat the valuable intermediate classes after the worthless classes have been removed.

14. An apparatus for recovering metal from submerged metal bearing deposits comprising a float adapted to be held adjacent the submerged deposit, means on the float for excavating the material of the deposit, a deep box double current classifier on the float, devices for rejecting the worthless classes including means for causing material of the deposit and water to flow through said classifier to allow the fine classes and excess water to flow overboard, and jigs on the float for treating the valuable intermediate classes after the worthless classes have been removed.

Dated the 23rd day of April, 1923.

JOHN FLESHER NEWSOM
